UNITED STATES PATENT OFFICE.

THEODOR KIRCHEISEN, OF DESSAU IN ANHALT, AND JOHANNES GÜRTLER, OF OFFENBACH-ON-THE-MAIN, GERMANY, ASSIGNEES, BY MESNE ASSIGNMENTS, TO GRASSELLI DYESTUFF CORPORATION, OF NEW YORK, N. Y., A CORPORATION OF DELAWARE.

PROCESS FOR PRODUCING FAST DYEINGS ON THE FIBER.

No Drawing. Application filed January 21, 1927, Serial No. 162,673, and in Germany January 23, 1926.

A known method of producing fast dyeings on the fiber consists in impregnating the fiber with a compound adapted to be coupled and then treating the fiber with a solution 5 of a diazo compound. In cases in which the compound adapted to be coupled has a certain affinity for the fiber it is sufficient merely to wring out the impregnated fiber and to conduct the coupling without previously drying. In producing printed colors, the material is previously prepared with a compound adapted to be coupled, such as 10 for example 2-hydroxynaphthalene, and is printed with a thickened diazo-solution; or 15 the material may be printed with a mixture of an alkali compound of a 2-hydroxynaphthalene carboxylic acid arylamide and a stable diazo compound, after which the material is steamed or exposed to the air and 20 the dyeing developed by treatment with an acid.

In the known process difficulties are associated with the diazotization. By the 25 present invention these difficulties are avoided and the process is conducted very simply by carrying out the preparation of the diazo compound on the fiber where it unites directly with the coupling component. The preliminary preparation of a diazo-solution or the use of a stable diazo compound is accordingly unnecessary.

In the copending application Serial Number 62,149 filed October 12, 1925, there are described preferred procedures for the preparation of diazo compound on the fiber 35 and its combination with coupling component present on the fiber. We do not claim what is disclosed and claimed in the mentioned application but only an improvement of said invention.

40 According to the present improvement the invention may be carried out as follows:

The fibrous material, such as artificial silk consisting of cellulose acetate, pelts, hairs, feathers, after having been impregnated 45 with a mixture containing a diazotizable compound, a compound adapted to be coupled and a nitrite is treated with an acid medium, preferably in the same bath by adding an acid agent to the bath.

50 If in the dyeing of pelts, hairs, feathers or

the like two baths are used, the goods to be dyed, which have been saturated with the said mixture, are wrung out or centrifuged and then brought into an acid bath, to which 55 some nitrite may advantageously be added.

To the dye bath may be added materials necessary for the so-called "killing process" in order to decrease and purify the pelts, hairs or the like which are to be dyed and to 60 make them receptive of the dye. Also materials which protect fibers may be added to the bath.

The invention may also be carried out by 65 treating the fiber with a mixture of a compound adapted to be coupled and a nitrite and then, after drying, with a solution containing a salt of a diazotizable base, preferably with an addition of an organic acid. One of the treatments with chemicals may 70 be executed by printing.

If the fiber is impregnated with a mixture containing a diazotizable compound, a compound adapted to be coupled and a nitrite, fast dyeings may be produced by printing 75 on an acid medium, for instance a mixture containing an organic acid.

The following examples, without limiting the invention, serve to illustrate in which manner the process may be carried out:

Example 1.—20 grams of cellulose acetate silk are handled for about 30 minutes at 60-70° C. in 500 cc. of a liquor containing per liter 0.4 gram of aminoazobenzene, 5 cc. of a solution of the sodium 2-hydroxynaphthalene (1:10), 50 cc. of Monopol soap solution (1:20) and 50 cc. of sodium nitrite solution (1:10). There are then added to the liquor 25 cc. of acetic acid of 6° Bé. and the acetate silk is handled for further 20-30 90 minutes at the said temperature. There is thus obtained a bright red dyeing.

Example 2.—20 grams of cellulose acetate silk are handled for about 30 minutes at 60-70° C. in 500 cc. of a liquor which contains per liter 0.3 gram of dichlorobenzidine, 10 cc. of sodium 2-hydroxynaphthalene solution (1:10), 10 cc. Turkey red oil of 50 per cent strength and 50 cc. of sodium nitrite solution (1:10). The development of the 100 dyeing is conducted as described in Example 1. There is obtained a bright orange dyeing.

Example 3.—20 grams of cellulose acetate silk are handled for about 30 minutes at 60–70° C. in 500 cc. of a liquor which contains per liter 0.1 gram of dianisidine, 1.2 gram of sodium 2-hydroxynaphthalene-3-carboxylate, 6 cc. of Turkey red oil of 50 per cent strength and 25 cc. of sodium nitrite solution (1:10). After development in the manner described in Example 1 there is obtained a medium blue.

Example 4.—20 grams of cellulose acetate silk are handled for about 30 minutes at 60–70° C. in 500 cc. of a liquor containing per liter 0.8 gram of dianisidine, 1.5 gram of sodium 2-hydroxynaphthalene-3-carboxylate, 50 cc. of Monopol-soap solution (1:20) and 50 cc. of sodium nitrite solution (1:10). After development in the manner described in Example 1 there is obtained a black dyeing.

Example 5.—In a bath containing per liter 2 grams of 5-nitro-2,4-diamino-1-methylbenzene, 25 cc. of Monopol soap solution (1:20), 10 cc. of a solution of sodium 2-hydroxynaphthalene (1:10) and 100 cc. of sodium nitrite solution (1:10), a well killed skin is handled for 2 hours at the ordinary temperature. After addition of 50 cc. of acetic acid of 6° Bé. the skin is further handled for about 30 minutes. There is obtained a brownish yellow dyeing.

Example 6.—In a bath containing per liter 3 grams of 5-nitro-2,4-diamino-1-methylbenzene, 25 cc. of Monopol soap solution (1:20), 4 grams of sodium 2-hydroxynaphthalene-3-carboxylate and 100 cc. of sodium nitrite solution (1:10), a skin is handled for about 30 minutes at the ordinary temperature. The further treatment is conducted as described in Example 5. There is obtained a copper red dyeing.

Example 7.—In a bath containing per liter 5 grams of 2-hydroxynaphthalene-3-carboxylic acid 2-methyl-4-chlorophenylamide, 10 cc. of Turkey red oil, 7 cc. of sodium hydroxide solution of 34° Bé, 5 cc. of formaldehyde of 30 per cent strength, 3.6 grams of 6-chloro-2-amino-1-methylbenzene, 100 cc. of sodium nitrite solution (1:10) and a fiber protecting agent, for example 5 cc. of Protectol Agfa, a skin is handled for 2 hours. The further treatment is conducted as described in Example 5. There is obtained a scarlet dyeing.

Example 8.—In a bath containing per liter 6 grams of 5-nitro-2,4-diamino-1-methylbenzene, 1.8 gram of 1-amino-naphthalene, 50 cc. of Monopol soap solution (1:20), 10 cc. of sodium 2-hydroxynaphthalene solution (1:20) and 300 cc. of sodium nitrite solution (1:10) a skin is handled for 2 hours. The further treatment is conducted as described in Example 5. There is obtained a dark brown dyeing.

Example 9.—In a bath containing per

liter 0.6 gram of 1-aminonaphthalene, 25 cc. of Monopol soap solution (1:20), 1 gram of sodium 2-hydroxynaphthalene-3-carboxylate and 150 cc. of sodium nitrite solution (1:10) a skin is handled for 2 hours. After further treatment as described in Example 5, there is obtained an olive green dyeing.

Example 10.—In a bath containing per liter 3.6 grams of 1-aminonaphthalene, 50 cc. of Monopol soap solution (1:20), 5.2 grams of sodium 2-hydroxynaphthalene-3-carboxylate and 300 cc. of sodium nitrite solution (1:10) a skin is handled for about 2 hours. After further treatment as described in Example 5 a black dyeing is obtained.

Example 11.—A skin is handled for about 2 hours in a bath containing per liter 4 grams of 1-aminonaphthalene, 50 cc. of Monopol soap solution (1:20), 5.2 grams of sodium 2-hydroxynaphthalene-3-carboxylate and 300 cc. of sodium nitrite solution (1:10). The skin is then wrung out and the dye is developed by introducing the skin into a fresh bath containing per liter 100 cc. of sodium nitrite solution (1:10) and 50 cc. of acetic acid of 6° Bé. There is obtained a black dyeing.

After dyeing the skin is well washed, which is also done in the other cases. For enhancing the fastness to rubbing the skin may be finally soaped.

Example 12.—The skin is handled at ordinary temperature for about 2 hours in a bath containing per liter 3.6 grams of 1-aminonaphthalene, 50 cc. of Monopol soap solution (1:20), 5.2 grams of sodium 2-hydroxynaphthalene-3-carboxylate, 100 cc. sodium nitrite solution (1:10), 5 cc. ammonia of 25 per cent strength and 30 grams of sodium chloride and the handling is continued for about 30 minutes after addition of 10 cc. formic acid of 85 per cent strength to the bath. When the dyeing is complete the skin is well washed. There is obtained a black dyeing.

Example 13.—3 grams of di-acetoacetic acid-ortho-tolidinide, 3 cc. of Turkey red oil, 4.5 cc. of sodium hydroxide solution of 34° Bé. and 2 grams of sodium nitrite are dissolved in 40 cc. of water. After addition of 40 grams of neutral starch-tragacanth thickening (6:100) the mixture is printed on unprepared goods. After drying there follows at the ordinary temperature a treatment with a solution of 5 grams of 2-chloro-1-aminobenzene hydrochloride and 20 grams of aluminium sulfate per liter. The goods are washed and soaped hot. There is obtained a clear yellow.

Example 14.—There are mixed together solutions of 5 grams of the sodium salt of the acid sulfuric acid ester of leuco-indigo in 20 cc. of water and 5 grams of di-acetoacetic acid-ortho-tolidinide, 5 cc. of Turkey

- red oil, 7.5 cc. of sodium hydroxide solution of 34° Bé. in 20 cc. of water and 4 grams of sodium nitrite in 10 cc. of water; to these solutions 50 grams of neutral starch-tragacanth thickening (6:100) are admixed. The unprepared goods are printed with the mixture, dried and then treated with a boiling hot solution containing per liter 0.95 gram of 2.5-dichloro-1-aminobenzenehydrochloride, 3 cc. of hydrochloric acid of 20° Bé., 50 grams of sodium chloride and 12.5 grams of aluminium sulfate. After they are washed the goods are soaped hot. There is obtained a green dyeing.
- 15 *Example 15.*—1.25 gram 2-hydroxynaphthalene-3-carboxylic acid phenylamide, 3 cc. of Turkey red oil, 2.2 cc. of sodium hydroxide solution of 34° Bé. and 3.8 grams of sodium nitrite are dissolved in 40 cc. of water. After addition of 40 grams of neutral starch-tragacanth thickening (6:100) the unprepared goods are printed with the mixture. They are then dried and introduced into a boiling hot solution containing per liter 0.95 gram of 2.5-dichloro-1-aminobenzene hydrochloride and 15 grams of aluminium sulfate. They are then washed and hot soaped. There is obtained a reddish orange dyeing.
- 20 *Example 16.*—1 gram of 2-hydroxynaphthalene-3-carboxylic acid-4-methoxyphenylamide, 3 cc. of sodium hydroxide solution of 34° Bé. 1.5 cc. of Turkey red oil and 2 grams of sodium nitrite are dissolved in 40 cc. of water. After addition of 40 grams of neutral starch-tragacanth thickening (6:100) the unprepared goods are printed with this mixture. After they have been dried they are treated with a boiling hot solution of 0.5 gram, 1-methyl-2-amino-5-nitrobenzene, 7.5 cc. of acetic acid of 30 per cent strength, 50 grams of sodium chloride and 5 grams aluminium sulfate per liter. After they have been rinsed they are soaped hot. There is obtained a Bordeaux tint.
- 25 *Example 17.*—The goods are saturated with a solution containing per liter 5 grams of 2-hydroxynaphthalene-3-carboxylic acid-3-nitrophenylamide, 7.5 cc. of sodium hydroxide solution of 34° Bé., 10 cc. of Turkey red oil (sodium salt) and 10 grams of sodium nitrite. After drying, the goods are printed with the mixture of 5 grams 1-methoxy-2-amino-5-nitrobenzene hydrochloride, 50 grams of lactic acid of 50 per cent strength, 445 grams of water and 500 grams of neutral starch-tragacanth thickening. They are then dried, washed, soaped hot, washed, first hot and then cold, and finally dried. There is obtained a bluish rose color.
- 30 *Example 18.*—The goods are saturated with a solution containing per liter 20 grams of di-acetoacetic acid-ortho-tolidinide, 30 cc. of sodium hydroxide solution of 34° Bé., 20 grams of Turkey red oil (sodium salt) and 20 grams of sodium nitrite. They are then dried and printed with a mixture of 16 grams 2-chloro-1-aminobenzene hydrochloride, 50 grams of glycolic acid, 434 grams of water and 500 grams of neutral starch-tragacanth thickening. They are then washed, soaped, further washed and dried. There is obtained a clear greenish yellow dyeing.
- 35 *Example 19.*—The goods are saturated with a solution containing per liter 25 grams of 2-hydroxynaphthalene, made into a paste with 25 grams of sodium hydroxide solution of 34° Bé. and 20 grams of Turkey red oil (sodium salt) and dissolved in water, and 30 grams of sodium nitrite. After the goods have been dried they are printed with a mixture of 30 grams of 1-aminonaphthalene hydrochloride, 30 grams of formic acid of 90 per cent strength, 440 grams of water and 500 grams of neutral starch-tragacanth thickening and are then washed and soaped. There is obtained a deep Bordeaux tint.
- 40 *Example 20.*—The goods are saturated with a solution containing per liter 20 grams of 2-hydroxynaphthalene-3-carboxylic acid phenylamide, 30 cc. of sodium hydroxide solution of 34° Bé., 20 cc. of Turkey red oil (sodium salt) and 30 grams of sodium nitrite. After they have been dried the goods are printed with a mixture of 24 grams of 2-amino-1-methoxybenzene-azo-1-aminonaphthalene (or the corresponding sulfamino acid), 8 grams of hydrochloric acid of 20° Bé., 40 grams of acetone, 24 grams of formic acid of 90 per cent strength, 80 grams of lactic acid of 100 per cent strength, 324 grams of water and 500 grams of neutral starch tragacanth thickening. They are then dried, washed and soaped hot. There is obtained a neutral black.
- 45 *Example 21.*—The goods are impregnated with a solution containing per liter 30 grams of 2,4-diamino-1-methylbenzene, 20 grams of Turkey red oil and 30 grams of sodium nitrite. They are then printed with a mixture consisting of 50 grams of oxalic acid, 450 grams of water and 500 grams of starch-tragacanth thickening. They are then washed and soaped as usual. The shade obtained is a dull brown.
- 50 What we claim is:
1. A process for producing fast dyeings on the fiber which consists in diazotizing a diazotizable amine on the fiber in presence of a compound to be coupled.
  2. A process for producing fast dyeings on the fiber which consists in treating the fiber first with a mixture containing a diazotizable compound, a compound adapted to be coupled and a nitrite, and then with an acid medium.
  3. A process for producing fast dyeings on the fiber which consists in treating the fiber first with a mixture containing a diazotizable compound, a compound adapted

- to be coupled and a nitrite, and then with an acid medium containing free nitrous acid.
4. A process for producing fast dyeings on the fiber which consists in treating the fiber first with a mixture containing a diazotizable compound, a compound adapted to be coupled and a nitrite, and then in the same bath with an acid medium.
5. A process for producing fast dyeings on the fiber which consists in treating the fiber first with a mixture containing a diazotizable compound, a compound adapted
- to be coupled and a nitrite, and then printing on an acid medium.
6. A process for producing fast dyeings on the fiber which consists in treating the fiber first with a mixture containing a diazotizable compound, a compound adapted to be coupled and a nitrite, and then printing on an acid medium containing an organic acid.
